GEORGE F. NUTTING, OF RANDOLPH, VERMONT.

Letters Patent No. 79,148, dated June 23, 1868.

IMPROVEMENT IN PUMPS.

The Schedule referred to in these Letters Patent and making part of the same.

TO ALL WHOM IT MAY CONCERN:

Be it known that I, GEORGE F. NUTTING, of Randolph, county of Orange, State of Vermont, have invented certain new and useful Improvements in Pumps; and I do hereby declare that the following is a full, clear, and exact description thereof, which will enable those skilled in the art to make and use the same, reference being had to the accompanying drawings, forming part of this specification, in which drawing—

Figure 1 represents a vertical central section.

Figure 2 is elevation thereof.

Similar letters indicate corresponding parts.

This invention relates to a pump, the barrel of which is open at its bottom end, and submerged in water. In the barrel is fitted a plunger, which receives its motion by a cage from below, and from the upper portion of said barrel extend the suction-pipe and the ascension or delivery-pipe. Suitable valves in the suction-pipe, and in the upper part of the barrel, between the suction and delivery-pipes, regulate the flow of the water. These valves are enclosed in valve-chambers, which are clamped to their places by keys passing through hook-shaped lugs, in such a manner that said valve-chambers can be readily attached or detached as occasion may require, and that but little time is required to keep the pumps in proper working order.

A represents the barrel of my pump, which is open at the bottom, and provided with a solid piston-plunger. B. Said barrel is secured to a standard, C, and the required motion is imparted to the piston by a cage, D, which straddles the barrel, and is suspended from a lever, E, the rod of the piston being secured to its lower cross-bar by a key or other suitable fastening, as shown in fig. 1.

The upper end of the barrel A is closed by a head, F, from which emanates the delivery-pipe G. Below the head is the valve-chamber H, and from the side of the barrel, close below said valve-chamber, extends the suction-pipe I. The valve chamber H is clamped to its place by keys a, which pass through hook-shaped lugs b, secured to the barrel A, and the joints are made tight by suitable packing-rings, c, above and below the valve-chamber. By driving the keys under the hook-shaped lugs, the head F and the valve-chamber H are clamped down tight to the barrel, and, by releasing said keys, the head and valve-chamber can be readily removed, and easy access can be had to the valves.

The suction-pipe is also provided with a valve, d, which is enclosed in a chamber, e, and this chamber is secured in its place by means of keys f, and hook-shaped lugs, g, in the same manner as the valve-chamber H.

In operating my pump, I immerse the lower open end in a bucket or cistern, and then I conduct the suction-pipe to the well, which may be situated below the bucket or cistern, or at a distance therefrom, and by giving motion to the plunger, the water is made to flow in through the suction-pipe and out through the delivery-pipe. If the piston descends, the valve in the top of the barrel closes, and the valve in the suction-pipe opens, and the water rises through said suction-pipe. If the piston rises, the valve in the suction-pipe closes, and the water in the upper part of the barrel is forced out through the valve under the delivery-pipe into this pipe. Whatever amount of water leaks past the piston or plunger is received in the bucket or cistern, in which the lower end of the barrel is immersed, and a chambered plunger can be used with very little packing, and at the same time said plunger remains filled. If the valves, or either of them, fail to work properly, they can be readily reached by driving out the keys a and f, and very little time is required to keep the pump in proper working order.

What I claim as new, and desire to secure by Letters Patent, is—

The combination of the open-bottomed barrel A, plunger B, upper removable part, containing the valve-chamber H, ascension-pipe G, suction-pipe I, and valve d, all arranged in the manner and for the purpose herein described and represented.

GEO. F. NUTTING.
